UNITED STATES PATENT OFFICE.

GUNDE BERGSTROM, OF LOS ANGELES, CALIFORNIA.

DESIGN FOR A TABOURET.

Application filed October 3, 1927. Serial No. 23,611. Term of patent 7 years

To all whom it may concern:

Be it known that I, GUNDE BERGSTROM, a citizen of the United States, residing at the city of Los Angeles, county of Los Angeles, State of California, have invented a new, original, and ornamental Design for a Tabouret, of which the following is a specification, reference being had to the accompanying drawing, forming part thereof.

The figure is a perspective view of a tabouret embodying my design.

I claim:

The ornamental design for a tabouret, substantially as shown.

GUNDE BERGSTROM.
